UNITED STATES PATENT OFFICE.

GEORGE WILLIAM OLIVER, OF HARROW, ENGLAND, ASSIGNOR TO J. LYONS AND COMPANY, LIMITED, OF LONDON, ENGLAND.

MEANS FOR INSERTING CARDS AND THE LIKE IN CARTONS OR SIMILAR CONTAINERS.

Application filed May 6, 1926, Serial No. 107,210, and in Great Britain July 14, 1925.

This invention relates to the insertion of cards and the like in cartons or similar containers and has for its object to provide an efficient device for automatically performing this operation in conjunction with existing types of packing apparatus, and which may be also adapted to operate as an independent unit.

Difficulty has been hitherto encountered in continuous operating machines for filling boxes, consisting mainly in the fact that exact timing of the operation at the moment when the card is to be inserted in a package is essential and that if the card does not enter the box neatly or at the precise moment breakdown is liable to occur with consequent diminution of the general output and efficiency of the device.

According to the present invention means are provided whereby a card or ticket or the like may be inserted into a carton or similar container precisely and rapidly at the moment when it is required to release said card or ticket from the inserting member, means also being provided for a preliminary feed of the card to the member actually adapted to insert the card in the container.

More particularly the present invention comprises a machine or apparatus for inserting cards and the like in cartons or similar containers comprising, a vacuum nozzle adapted to receive and hold a card when in a certain position, means for feeding a card to said vacuum nozzle when said nozzle is in said position and means operable when said vacuum nozzle reaches another position for breaking the vacuum and causing said vacuum nozzle to release the card.

When it is desired to employ the card inserting member in conjunction with continuously operating machines for filling boxes the timing of the device is so arranged that the aforementioned feeding operation of the card to the inserting member is effected automatically prior to the moment when the container is in a position ready to receive the card. The inserting member may consist of a suitably shaped air suction nozzle which is adapted to hold a card centrally and firmly in position so long as the necessary suction is maintained. When however the inserting member is required to release the card a suitable port provided in the suction nozzle is opened in any suitable man-

ner, thus destroying the vacuum and enabling the card to fall by gravity into the container.

In order that the invention may be more readily understood reference is directed to the accompanying drawings which are illustrative of one convenient manner of carrying the invention into effect and in which,

Figure 1 is a side elevation showing the principal operating members of the card containing and inserting apparatus.

Figure 2 is an end elevation of the apparatus shown in Figure 1 and

Figure 3 is a semi-diagrammatic view of the card inserting suction nozzle drawn to an enlarged scale.

Referring now to these drawings, wherein similar reference characters are employed to designate the same portions of the apparatus throughout the several figures, the numeral 2 represents a vertically positioned magazine adapted to receive a number of cards or the like in pile formation. Slidably located at the lower end of the magazine 2 is provided a knife or plunger 3 suitably arranged in known manner so as to receive the lowermost card of the pile at each successive reciprocation. Rigidly secured to the underside of the knife 3 is a projecting member 4 connected by a link 5 to the upper end of a bell-crank lever 6 suitably mounted at the end of a bracket-like member which is bolted to any convenient fixed portion of the apparatus. The other arm 7 of the lever 6 is connected to a further link 8 which in turn is connected to the upper end of a vertically movable rod 9. The rod 9 at its lower end is secured to the projecting lug 10 of a bracket member 11 having a longitudinal slot 12. A roller 13 is freely mounted at the lower end of the member 11 and is adapted to bear against the periphery of a cam 14 by the aid of a tension spring 15 fixed at one end to a stationary support 16 and at the other end to the movable bracket 11. The cam 14 is provided with a pin 17 which is adapted to enter the slot 12 and is moreover adapted to rotate about the axis of the pin 17 by means of an extension 18 of the cam disc which may be driven by the crank and crank pin drive indicated in dotted outline at A in Fig. 2. The bearing surface of the cam 14 is of such a shape that as it rotates the roller 13 will cause the bracket 11 and therewith the rod 9 to

reciprocate; this motion is transmitted to the recessed knife 3 through the link-work mechanism 8, 7, 6, 5, 4. Upon the forward stroke of the knife 3, containing a card from the magazine 2, said card is fed to the underside of a suction-nozzle 19 positioned vertically and in slidable engagement with a bracket 20 secured to the card magazine 2. The nozzle 19 is provided with a pipe connection 21 to any desired source of low pressure generation or vacuum producing apparatus. A guide member consisting of a rod 22 is attached to the upper end of the suction nozzle and is caused to reciprocate vertically by any suitable plunger mechanism, the upstroke being effected with the aid of a spring 23 secured at one end to a collar 24 on the suction nozzle and at the other end to the fixed bracket 20. The suction nozzle 19 which may be more clearly seen by Fig. 3 passes through a sleeve member 25 having an extension 26 bolted to the magazine 2 and contains a central bore 27 having lateral ports 28 and 29 communicating with an annular chamber 30 in direct communication with the suction supply pipe 21. In this manner so long as the ports 28 and 29 are within the region of the chamber 30 suction is maintained in the nozzle 19 and a card which is placed under the mouth of said nozzle so as to abut against a stop 31 will be gripped and held in close engagement. When however the nozzle is lowered until the collar 24 reaches the position 24^a the ports 28 and 29 are lowered to a position 28^a and 29^a below the chamber 30, and as these ports are now open to the atmosphere the vacuum is destroyed and the card is immediately released.

When in operation, cartons or similar packages are placed with the upper surface of the contents exposed upon a rotating table or other continuous conveying means of known type so located that each carton or the like may in turn pass below the suction nozzle 19. As a carton approaches feeding position the mechanism associated with the rod 9 and knife 3 is timed so as to cause the knife 3 to recede and receive a card from the magazine 2. The card is then pushed forward by the knife 3 to a central position below the mouth of the suction nozzle 19, this being determined by the projecting stop 31. The carton conveying means is now timed so that immediately a carton is located underneath the suction nozzle 19 the movement

of said conveying means is momentarily suspended and the rod 22 is plunged downward by any suitable means a distance sufficient to enable the mouth of the nozzle to remain immediately over the open top of the carton. When however this position is reached the ports 28 and 29 will have assumed the position 28^a and 29^a respectively (Fig. 3) thus permitting atmospheric air to enter and enable sudden release of the card whereby it may fall directly into the box or container. At this stage the conveying means is set into operation and the suction nozzle reinstated to its original elevated position and the operation may be repeated for each subsequent card and container in the manner already described.

It will be understood that any suitable means may be employed for conveying the cartons and the like and that the extent to which the suction nozzle may be lowered depends upon the height of the carton. Also any convenient means may be provided whereby the suction nozzle ports may be caused to destroy the suction at the requisite distance above the carton.

It will be seen that this improved device provides a practical and efficient means for ensuring a firm grip of the card before insertion and equally efficient means for a sudden release thereof at the requisite moment.

What I claim and desire to secure by Letters Patent is:—

In a machine for inserting blanks in containers, in combination, a vertical magazine containing a pile of blanks, a tubular downwardly depending movable vacuum nozzle disposed vertically and supported adjacent said magazine, suction means associated with said vacuum nozzle, a reciprocating knife member operated by cam and link mechanism and arranged to feed successively a lowermost blank from the magazine to the underside of said vacuum nozzle, a suction chamber surrounding a hollow central tube portion of said nozzle, the tube portion having ports normally communicating with said suction chamber, said ports being brought into communication with the atmosphere to break the vacuum when said nozzle is in a lowered position whereby the blank is released to fall vertically from the mouth of said nozzle into a container.

In witness whereof I affix my signature.

GEORGE WILLIAM OLIVER.
